CONTROLLING MECHANISM FOR ROLLER FIRE-SHUTTERS.

1,254,149.

Specification of Letters Patent. Patented Jan. 22, 1918.

Application filed April 14, 1916. Serial No. 91,138.

To all whom it may concern:

Be it known that I, WILLIAM G. MILLER, a citizen of the United States, residing at Toronto, in the county of York, Province 5 of Ontario, Canada, have invented certain new and useful Improvements in Controlling Mechanism for Roller Fire-Shutters; and I do declare the following to be a full, clear, and exact description of the invention, 10 such as will enable others skilled in the art to which it appertains to make and use the same, reference being had to the accompanying drawings, and to the characters of reference marked thereon, which form a part of 15 this specification.

This invention relates to roller fire shutters and consists in the novel features of construction and arrangement of parts as hereinafter set forth and claimed.

20 The invention has for its objects the provision of simple and efficient controlling means for use in connection with a fire door or shutter carried upon a spring tensioned roller, whereby the spring for actuating the roller may be set under the required tension to normally support the shutter and secured by disengageable locking means actuatable under a given temperature for automatically releasing said spring and allowing said 30 shutter to drop, and wherein provision is made through the employment of mechanism actuatable by the force of the spring when released for imparting movement to start and insure the downward movement of 35 the shutter, also for engaging and re-locking the spring under a reduced tension so as to cushion the shutter upon reaching the limit of its downward travel and for retaining said spring under a partial or reduced tension sufficient to exert upon the 40 roller the required rotary force to permit and assist in the raising of said shutter after it shall have been automatically dropped.

45 A preferred form of embodiment of the novel features of the present invention by which the above objects are attained is illustrated in the accompanying drawings, in which,

50 Figure 1 is a front elevation of a shutter having a portion of the housing and spring tensioned barrel or roller contained therein broken away to show the internal arrangement of parts, and showing the controlling mechanism attached to the end of the hous-

ing in the locked position for automatic 55 operation.

Fig. 2 is an end elevation of the end portion of the housing carrying the controlling mechanism set in the locked position, as shown in Fig. 1, and showing the shutter 60 in the raised position in engagement with a spring pressed starting plunger.

Fig. 3 is also an end elevation of the housing showing the controlling mechanism released from engagement with its locking lever and engaged with the starting plunger by which the downward movement of the shutter is accelerated, the shutter being shown in the down extended position with one of the guide ways in which it travels 70 removed.

Fig. 4 is a fragmentary vertical sectional view through a portion of the housing and the controlling mechanism, taken on dotted line 4-4 of Fig. 2. 75

Referring to the parts of the device by the characters of reference marked on the several views of the drawings, 0 indicates a housing containing a revoluble barrel or hollow roller 1, upon which a flexible apron 80 or shutter 2 is supported to wind thereon and to travel in vertical guides 3 arranged at opposite sides of a doorway or opening to be closed by the shutter. A coiled spring 4 for exerting rotary force upon the barrel 85 or roller 2 is contained within said roller and is fixedly attached thereto at one end. The opposite end of this spring is secured axially to the inner end of a stub shaft or arbor 5, which is rotatably embraced in one 90 end of said roller, and which is journaled at its outer reduced end 6 to extend through a bearing 7 in the end wall or head 8 of the housing 1. Keyed to the reduced end 6 of the stub shaft 5, exteriorly of the housing, 95 is a pinion 9, the teeth of which mesh with the teeth of an internal gear 10 which is journaled to rotate on a stud 11 anchored in a boss 12 on the head 8 of the housing, and which is retained thereon by a cotter 100 pin 13 extended through the outer end of said stud, as clearly shown in Fig. 4.

Before mounting or positioning the gear 10 in engagement with the pinion 9 said pinion and its shaft 5 are given the required 105 number of revolutions to wind and charge the spring under the necessary tension to transmit and exert upon the roller 2 rotary

force sufficient to support and counterbalance the weight of the shutter 3. The gear is then locked against rotation with the pinion under the unwinding influence of the spring 5 by disengageable locking means for normally retaining the roller under the fixed tension of said spring to enable the raising and lowering of the shutter through the application of upward or downward pressure thereon. This locking means comprises a latch lever 14 which is positioned vertically adjacent the periphery of the gear 10 and is pivotally connected at one end by a stud or rivet 15 to a bracket 16 projecting from the head 8 of the housing to swing outwardly thereon, and formed in the inner face of a lateral projection 17 on said lever is a transverse depression or keeper 18 having an outwardly inclined shoulder 19 against which the radially projecting end of a locking pin 20, which is seated in a boss or lug 21 on the face of the gear 10, is adapted to engage. Said lever is normally held in locked engagement with this pin by means of a flexible tie rod or cable 22, one end of which is attached to a support 23 on the housing and the opposite end is secured to the free end of said lever. Inserted in the body of said cable is a fusible link 24 adapted to fuse at a given temperature to release the lever for disengagement by the pressure of the locking pin 20 upon the inclined shoulder 19 thereof, which will cause said lever to swing outwardly and release the gear to rotate with the pinion under the unwinding action of the spring which latter in relaxing its tension upon the roller will allow the shutter to drop and close the doorway or opening. (See Figs. 1 and 3.)

40 To insure the starting of the shutter on its downward movement and to provide for retaining the spring under a relaxed tension to cushion the fall of the shutter and to maintain the roller under sufficient rotary tension to assist in raising the shutter after having been automatically lowered, the following mechanism is employed: As best shown in Fig. 2, a rod or plunger 25 is positioned adjacent the periphery of the gear 10 upon the side opposite the locking lever and is mounted to slide vertically through spaced bearing lugs 26 and 27 projecting laterally from the head 8 of the housing. Embracing the upper end of the plunger and interposed between a collar 28 thereon and the bearing lug 26 is an expansive coiled spring 29, under the tension of which said plunger is normally held extended upwardly in contact at its upper end with a limiting stop 30 extending from the head 8 of said housing. The lower edge of the shutter 3 which is provided with a base strip 31 and stiffening angle 32 has secured thereto at one end by bolts or rivets 33 a curved arm 34 which extends around the vertical guide 3 and terminates in a foot 35 in line with the lower end of the plunger 25 with which it is adapted to engage when said shutter is in the raised position, as shown in Fig. 2. An impact collar 36 is secured to the plunger between the bearings 26 and 27 and is so positioned as to lie in the path of travel of a striking lug 37 projecting from the periphery of the gear 10 and by engagement with which said plunger is driven downwardly against the arm 34 of the shutter, being limited in its downward movement by the engagement of said collar with a cushioning pad 38 mounted on the bearing 27, and which also serves as a stop to limit the rotation of said gear and to lock the spring under a remaining tension, as shown in Fig. 3.

With the parts set in the position shown in Fig. 2, the operation of the device will be understood as follows: Upon the release of the locking lever by the fusing of the link, the gear being released will be driven through the rotation of the pinion by the unwinding action of the spring, and as the striking lug of said gear engages the impact collar of the plunger said plunger will be forced downwardly against the tension of its spring and driven at its lower end against the engaging arm of the shutter. The force of the plunger thus exerted upon the shutter following the relaxing of the tension of the spring upon the roller will start said shutter on its downward course and upon reaching the limit of its travel said collar will have engaged its limiting stop to check the gear against further rotation. This action will re-lock the spring and retain the roller under a reduced tension which will serve to retard and cushion the shutter at the completion of its travel, and which will maintain said roller under sufficient rotary lifting force exerted on said shutter to enable the latter to be raised in case of emergency without requiring the resetting and locking of the spring under its normal tension.

It is obvious that the structural details herein disclosed may be varied without departing from the essential features, and the invention is presented as including all such modifications and changes as properly come within the scope of the following claims.

I claim:

1. In controlling means for fire shutters, the combination of a roller having a shutter thereon, a spring in said roller connected at one end thereto, a shaft extending into said roller and connected to the opposite end of said spring, releasable means for locking said shaft against rotation under the tension of said spring, and means movable into engagement with the shutter and actuatable by said locking means when released to impart a downward movement to the shutter and to relock said shaft under

a partial tension of said spring to retard said shutter at the limit of its downward travel.

2. In controlling means for fire shutters, the combination of a roller having a shutter thereon, a projecting arm on said shutter, a shaft journaled in the end of said roller, a spring connected at one end to said shaft and at its opposite end to said roller, releasable locking means connected with and restraining said shaft against rotation under the tension of said spring, a spring pressed plunger movable into engagement with the arm of said shutter and actuatable by said locking means when released to impart a downward movement to said shutter, and a stop to limit the movement of said plunger and to relock said shaft under tension of said spring.

20 3. In controlling means for fire shutters, the combination of a roller having a shutter thereon, a spring in said roller connected at one end thereto, a shaft extending into said roller and connected with the opposite end of said spring, releasable locking means connected with and restraining said shaft against rotation under the tension of said spring, starting means associated with the locking means and with the shutter and actuatable by said locking means when released to engage and start said shutter downwardly and thereafter relock said shaft and said spring under a partial tension to retard and cushion the shutter in its downward travel.

4. In controlling means for fire shutters, a housing, a roller journaled in said housing and carrying a shutter thereon, a shaft extending into said roller, a spring connected at one end to said shaft and at its opposite end to said roller, a pinion on said shaft, a gear mounted on said housing in mesh with said pinion, releasable locking means for restraining said gear against rotation, a spring pressed plunger mounted on said housing and movable into engagement with said shutter, a striking member on said gear

adapted to engage said plunger when released by said locking means, and means to limit the movement of said plunger and to relock said gear.

5. In controlling means for fire shutters, the combination of a housing, a roller journaled in said housing and carrying a shutter thereon, a shaft journaled in said housing and extending into one end of said roller, a spring in said roller connected at one end thereto and at its opposite end to said shaft, a pinion on said shaft, a gear journaled on said housing in mesh with said pinion, releasable locking means for restraining said gear against rotation under the tension of said spring, a spring pressed plunger mounted on said housing and movable into engagement with said shutter, an impact member on said plunger, a striking member on said gear adapted to engage said impact member upon the release of said locking means to drive said plunger against said shutter, means to limit the movement of said plunger and said gear.

6. In controlling means for fire shutters, the combination of a roller having a shutter thereon, a projecting arm on said shutter, a shaft extending into said roller, a spring connected at one end to said shaft and at its opposite end to said roller, a pinion on said shaft, a gear mounted on a fixed support in mesh with said pinion, releasable locking means for restraining said gear against rotation, a spring pressed plunger mounted on a fixed support adjacent said gear and movable into engagement with the arm on said shutter, an impact member on said plunger, a striking member projecting from said gear adapted to engage said impact member upon the release of said locking means to drive said plunger against the arm of said shutter, and a stop with which said impact member engages to limit the movement of said plunger and said gear.

In testimony whereof, I sign this specification.

WILLIAM G. MILLER.
